United States Patent Office.

EDWARD BOURNE, OF PITTSBURG, PENNSYLVANIA.

Letters Patent No. 97,864, dated December 14, 1869.

IMPROVEMENT IN STEAM-GENERATORS.

The Schedule referred to in these Letters Patent and making part of the same.

To all whom it may concern:

Be it known that I, EDWARD BOURNE, of Pittsburgh, in the county of Allegheny, and State of Pennsylvania, have invented a new and useful Improvement in Steam-Generators; and I hereby declare that the following is a full, clear, and exact description thereof, reference being had to the accompanying drawings, forming part of this specification, and to the letters of reference marked thereon.

The nature of my invention consists in the construction, as hereinafter described, of a boiler, of distinct metallic globular or other-shaped hollow parts or chambers, united in groups or clusters by screwing the neck of one into the bottom of the other, and providing each spherical chamber with an inlet and outlet-pipe, of different lengths, leading into the one immediately connected to it, or into a steam or water-reservoir, by which a natural, continuous, and perfect circulation of water in said several chambers is maintained at all times during the operation of generating steam.

To enable others to understand, make, and use my improved steam-generator, I will proceed to describe its construction and operation by reference to the annexed drawings, in which—

Figure 1 represents a front elevation of my apparatus, partly in perspective and partly in section.

Figure 2 represents a transverse vertical section of a cluster of spherically-shaped chambers attached to and hanging in a vertical line beneath a steam-receiver.

Figure 3 represents a section of the generator on a horizontal plane, through the necks of the spherical chambers.

Figure 4, vertical section of the safety-valve.

All the drawings are lettered, and similar letters denote like parts in the several views.

To construct my apparatus, I make a number of metallic bottle-shaped chambers, B, each provided with a short neck, a, and with a hole in its bottom, corresponding in size with that neck.

Through the necks a of these chambers are two vertical openings, one consisting of a short tube, T, just long enough to reach and communicate with the interior, the other, S, being a much longer tube, and extending into the chamber, and within one inch of its bottom.

On the necks a of these several chambers B, a screw is cut, by which they may be united the one to the other, in clusters, by screwing the neck of one chamber into the hole in the bottom of the other next above it.

When several of these chambers have been thus united, they are then attached to a steam-receiver,

A, by screwing the neck a of the upper chamber thereinto, as represented in the drawings.

Where the boiler is intended for the generation of large quantities of steam, two or more of these clusters may be attached to one receiver, by direct connection therewith, or by attaching them to vertical or horizontal flues or pipes extending therefrom, where-with boilers of different forms and dimensions may be built up, as the nature of the case may require.

The steam-receiver A, represented as being above the spherical chambers B, is provided with a steam-conduit pipe, R, of ordinary construction, and within a safety-valve, L.

This boiler is provided with an outside casing, C, which rests upon a fire-pot, P, furnished with the usual grate-bars, door, ash-pit, &c.

This fire-pot is constructed with double walls, leaving a space between the two, in which water is allowed to circulate, the requisite quantity being furnished by a branch, g, of the supply-pipe m entering at any convenient point.

This supply-pipe m is attached directly to, and communicates with the interior of the spherical chambers B, by which an equable supply of water may be had in the entire apparatus; and, to assist in keeping up a circulation, the pipe is made to enter the lowermost chamber of a series.

On fire being applied, the water in these lower chambers will be affected first, and, as the temperature increases, the water will expand and rise through the short pipe T, into the chamber above, a constant supply being afforded by the water at the same time descending the long pipe S, producing a strong current, the direction of which is indicated by the arrows in fig. 2.

As the heat increases, this current will be greatly augmented as it travels from chamber to chamber, so that on reaching the uppermost chambers of a series or cluster, the velocity attained by this time will be most rapid and continuous, sufficient in power to prevent the setting of any sediment tending to form an incrustation in the boiler, a thing heretofore unaccomplished.

Having thus stated the nature of my invention, its construction and operation,

What I claim, is—

The construction, combination, and arrangement of the boiler A, chambers B, and passages T, substantially as described.

EDWARD BOURNE.
